FIG. 4

UNITED STATES PATENT OFFICE

EDWARD A. CUNNIFF, OF THOMPSONVILLE, CONNECTICUT, ASSIGNOR TO BIGELOW-SANFORD CARPET CO., INC., A CORPORATION OF MASSACHUSETTS

YARN-WINDING MACHINE

Application filed May 8, 1928. Serial No. 276,044.

This invention relates to yarn winding machines, and more particularly to that class of winding machines wherein the yarn package being formed is surface driven frictionally from a rotating driving roll.

It is now the ordinary practice to wind yarn which is to be used as the warp threads in weaving, into packages, and support these packages in a creel frame from which a multiplicity of threads are drawn and wound side by side on a warp beam. If the yarn packages contain different amounts of yarn it results in the frequent stoppage of the warping machine to piece up ends and consequent loss of production.

One of the objects of the present invention is to improve yarn winding machines in order that yarn packages of predetermined size may be produced so that when a multiplicity of such packages of the same yarn size are placed in the creel frame and wound upon the warp beam, fewer or substantially no stoppages of the warping machine become necessary due to the premature running out of some of the yarn.

An improved feature of the present invention consists in automatic means which becomes effective to stop the winding operation of any one yarn package when that yarn package has reached a predetermined size.

The invention and new combination of parts will best be made clear from the following description and accompanying drawings of one good form thereof.

In the drawings—

Fig. 1 is a perspective view with parts broken away showing sufficient portions of the yarn winding machine containing the present invention to make clear the construction and operation thereof;

Fig. 2 is a perspective view of a slightly modified form in the details constituting features of the present invention;

Fig. 3 is a somewhat enlarged section on the line 3—3 of Fig. 2; and

Fig. 4 is an enlarged side elevation of a yarn winding machine containing the present invention, showing the relation of parts when the yarn package has reached its predeter-

mined size, and winding of yarn on the package is to be stopped.

The general construction of the yarn winding machine may be similar to those of similar character now well known, and as shown such machine comprises the frame 1 which may be of a size and extent to support a plurality of yarn winding mechanisms, only one of which is shown in the drawings.

Mounted in a suitable bracket 2 secured to the machine frame are the bearing arms 3 for a driving roll 4 which constitutes the driving means for the yarn package which normally rests thereon during the winding operation. These parts may be of usual construction and the driving roll 4 may be driven from any suitable source of power now well known, and not therefore herein illustrated.

Pivottally mounted on the bracket 2 at 5 is a yarn package lifter 6 from each side of which are the rearwardly extending lifter arms 7 having a transverse portion 8 which, during normal winding operations, occupies the position back of the driving roll 4, as indicated in Fig. 1. The lifter frame 6 is also provided with a yarn guide 9 which directs the yarn to the yarn package as it is being wound.

Extending between suitable uprights 10 of the machine frame is a transversely extending shaft 11 on which is loosely mounted an arm 12 which supports the yarn holder. The yarn holder may be of any of the present well known constructions and as shown in the present instance of the invention comprises the arms 13 having a suitable bearing for the core or yarn holder proper 14, the construction being such that as the yarn is wound upon the yarn holder or core 14 by surface engagement with the driving roll, the yarn holder will be gradually raised as the yarn package increases in size.

The parts constituting the yarn holder may be variously contrived, the essential in this respect being that the yarn holder will be gradually raised as the yarn packages increase in diameter.

The yarn *a* may be supplied from any suitable source as for instance from the spools 15 from which the yarn passes through and over suitable guides 16, 17, 18, and then under a

guide bar 19 from which the yarn passes to the yarn guide 9, and suitable traversing mechanism may be employed as usual in this class of machine and now well known, for traversing the yarn longitudinally of the yarn holder or core 14. The parts so far described may be of usual construction and the details thereof form no essential part of the present invention.

10 The lifter frame 6 has mounted thereon, as more clearly shown by Fig. 4, the dog 20 which may be supported for rocking movement upon a shaft 21 carried by the lifter frame. The dog 20 has a catch portion 22 which is adapted to be engaged by the end 23 of a vibrator 24 mounted upon the shaft 25, and the latter is given a continuous rocking movement during the winding operation from a suitable source of power now well understood in the art.

15 Extending upwardly from the uprights 10 is a bracket or support 26, one at each side of the winding mechanism, and extending between the brackets or supports 26 is a shaft 27 on which is loosely mounted a trip arm 28 constituted as a lever adapted for vertically swinging movement about its axial support 27. In order to limit the downward movement of the trip arm or lever 28 a suitable 20 stop is provided, which in the present instance consists of a pin 29 extending from an arm 30 which is secured to the shaft 27 or one of the brackets 26.

25 Pivottally connected to the trip arm 28 at 31 is the dog controller 32 which is normally under the influence of a spring 33, one end of which is secured to the dog controller at 34 and the other end to a fixed part 35. The fixed part 35 in the present 30 instance of the invention is formed as a projection from a plate 36 having an opening 37 and secured in adjusted position by a screw bolt 38, the result being that the tensioning effect of the spring 33 upon the dog controller 32 may be conveniently varied by 35 adjustment of the plate 36 on the trip lever 28.

40 Mounted for adjustment on the trip lever 28 is a stop plate 39 which may be secured in adjusted position on the trip arm by a bolt 40 which passes through an opening or slot 41, as indicated in Figs. 1 and 2. The lower portion of the stop plate 39 has a projection 42 on which the inner end portion of the dog controller normally rests under the action of 45 the spring 33.

45 In accordance with the present invention the dog controller 32 is connected to the dog 20 by a rod or connection 43. The upper end of the rod 43 is connected to the dog controller at 44 and its lower end is connected to the dog 20 through a pin 45 to which the lower end 46 of the rod 43 is secured, the construction being such that during the winding operation, as indicated in Fig. 1, the dog 20 50 is maintained in an inoperative relation to its

associated vibrator and the winding of the yarn upon the yarn holder or core continues uninterruptedly.

55 Secured to one of the arms 13 of the yarn holder is a bracket 47 to which is secured a trip finger 48, the upper portion of which is turned at 49 to present a bunter adapted to engage a projection 50 carried by the trip arm 28 and lift the latter when the yarn package has reached a predetermined size, the construction being such that when this action takes place and the trip arm 28 is lifted the dog controller will act upon the dog 20 to throw its catch end 22 into the path of the vibrator 24 with the result that the lifter frame 6 will be turned upon its pivotal support 5 and cause the lifter arm 7 to move outwardly about the pivot point 5 as a centre, thereby separating the yarn package from its driving roll.

60 It may be desirable at times to vary the amount of yarn contained in the yarn packages, and to this end the trip finger 48 is provided with a slot 51 by which the trip finger is adjustably secured to the yarn holder or bracket 47 by the securing bolts 52. It will be evident from the adjustable character of the trip finger 48 that the yarn package may be varied in size because as the yarn package increases in size and lifts the yarn holder and trip finger, the position of the trip finger will define when and at what time the yarn package and its driving roll shall have separated into the position indicated by Fig. 4.

65 Since the dog 20 is mounted upon the lifter frame 6 and the lifter frame turns about its pivotal support 5, the dog will take a downwardly curved path under the influence of the vibrator so that a flexible connection is necessary between the trip arm and the dog, and this is effected in the present instance of the invention by the yielding character and mounting of the dog controller on the trip arm under the influence of the spring 33.

70 From the construction described it will be apparent that a simple and yet effective means is provided for insuring the same amount of yarn in the yarn packages produced by the winding machine and the yielding connection between the trip arm and dog through the yieldable action of the dog controller permits the movement of the lifter frame without disturbance of any of the operative relations of the automatic winding stop motion.

75 As herein before stated Figs. 2 and 3 show a slightly modified form of the details of the invention, wherein the trip arm 28, which may be constructed substantially as in the preferred form of the invention already described, has mounted on it the dog controller 32 by the pivotal connection 31 as before, and extending downwardly from the dog controller is the rod or connection 53 having interposed in its length a yielding portion by 80 means of a spring 54 the lower end portion of 85

which may be properly connected to the dog 20 by means of a pin 55 extending therefrom.

Pivottally connected to the trip arm 28 is a latch 56 which, as shown, Fig. 3, is pivoted at 57 to a bracket 58 secured to the trip arm 28. The latch 56 has a catch end 59 which normally engages over the inner end portion of the dog controller 32, Fig. 3, and the opposite end portion of the latch 56 is provided with a shoe or abutment 60 which is adapted to be engaged by the upper portion of the trip finger 48 when the yarn package has reached the predetermined desired size. From the description described it will be noted that the dog controller 32 in the modified form of the invention normally holds the dog 20 in its operative relation with the associated vibrator, but when the trip finger 48 engages the end or shoe 60 of the latch 56 the catch end 59 of the latch will be disengaged, with the result that the outer end of the dog controller 32 will drop, thereby permitting the dog 20 to pass into operative relation with its associated vibrator, and through the train of mechanism already described as constituted by the lifter frame 6 and its associated parts, the yarn package will be separated from its driving roll in a manner as hereinbefore already explained.

Inasmuch as the latch 56 has the shoe 60 which normally holds the latch in engagement with the dog controller, it is desirable to control the amplitude of latch movement, and in the present instance of the invention this is effected by means of a stop plate 61 having a laterally turned portion 62 upon which the shoe portion of the latch may rest during the winding operation. The stop plate 61 may be adjustably secured to the trip arm 28 by means of the slot 63 formed in the stop plate and the securing screw or bolt 64 which is passed therethrough.

When the yarn package has been completed and the dog controller has been released by its latch, it may be desirable in some instances to limit the position of the dog controller as it is moved again into operative relation with this latch and to this end the trip arm is provided with a pin 65, the lower end portion of which is outturned as at 66 below the inner portion of the dog controller, so that as the dog controller is manually returned to its yarn winding position, the outturned end 66 of the pin limits to its amplitude of movement to effect a proper relation of the inner end of the dog controller and the latch.

Claims:

1. In a yarn winding machine, the combination of a yarn package driving roll, a yarn package holder movable towards and from said roll, a power operated vibrator, a dog adapted to engage said vibrator, a pivotally mounted lifter frame on which the dog is

mounted, lifter arms extending from the lifter frame for engaging and moving the yarn package away from the driving roll, a pivotally mounted trip arm having a pivotally mounted dog controller, connections between the dog and dog controller, and means actuated by the yarn package holder to effect movement of the dog by the dog controller into engagement with the vibrator when the yarn package has reached a predetermined size to swing the lifter frame and cause the lifter arms to engage the yarn package to disengage the yarn package from its driving roll.

2. In a yarn winding machine, the combination of a yarn package driving roll, a yarn package holder movable towards and from said driving roll, a trip arm mounted for movement independent of and above the holder, a dog controller pivotally mounted on the trip arm, a dog and vibrator, a lifter frame to which the dog is pivotally connected, lifter arms carried by the lifter frame and connections between the dog controller and dog for operatively relating the dog and vibrator when the yarn package has reached a predetermined size to swing the lifter frame and cause the lifter arms to engage and lift the yarn package from its driving roll.

3. In a yarn winding machine having a driving roll and yarn package holder, a vibrator, a pivotally mounted lifter frame, lifter arms extending upwardly therefrom to engage and lift the yarn package, a dog mounted on the lifter frame and adapted to be actuated by the vibrator to swing the lifter frame and cause the lifter arm to disengage the yarn package and driving roll, and means for controlling the operative relation of the dog and vibrator, comprising a pivoted trip arm independent of and above the yarn package holder, a dog controller mounted for swinging movement relative to the trip arm, and connections between the dog and dog controller for operatively positioning the dog and vibrator to disengage the yarn package and driving roll when the yarn package has reached a predetermined size.

4. In a yarn winding machine, the combination of a yarn package driving roll, a yarn package holder movable towards and from the driving roll, a lifter frame mounted for swinging movement, lifter arms extending upwardly from the lifter frame and having a transverse portion normally back of the driving roll, a vibrator, a dog mounted on the lifter frame and adapted to be operated by the vibrator to separate the yarn package and driving roll, a trip lever independent of and above the yarn package holder provided with a dog controller mounted for swinging movement on the trip lever, connections between the dog controller and dog, and a trip finger projecting from the yarn package holder to cause the dog controller to operatively position the dog and vibrator when the

yarn package has reached a predetermined size.

5. In a yarn winding machine, the combination of a yarn package driving roll, a yarn package holder movable towards and from the driving roll, a vibrator, a dog adapted to be operated by the vibrator, a lifter frame carrying the dog, lifter arms mounted on the lifter frame to separate the yarn package and driving roll, a trip lever independent of and above the yarn package holder, yielding connection between the trip lever and dog, and a trip finger movable upwardly with the yarn package holder and acting through the trip lever and its yielding connection with the dog to operatively relate the dog and vibrator and cause the lifter frame and lifter arms to separate the yarn package and driving roll when the yarn package has reached a predetermined size.

10. In a yarn winding machine having a yarn package driving roll and a yarn package holder, means for separating the yarn package from the driving roll when the yarn package has reached a predetermined size, comprising in combination, a vibrator and dog, a lifter frame having lifter arms and carrying said dog, a trip lever mounted for independent movement above the package holder, a trip finger mounted on and extending upwardly from the package holder and gradually moved towards the trip lever during the winding operation, a dog controller pivotally mounted on the trip lever for pivotal movement thereon, and connections between the dog controller and dog for operatively positioning the dog and vibrator when the trip finger is raised a predetermined amount.

40. 7. In a yarn winding machine having a yarn package driving roll and a yarn package holder, means for separating the yarn package from the driving roll when the yarn package has reached a predetermined size, comprising, in combination, a pivotally mounted lifter frame having lifter arms, a transverse connection between the lifter arms normally back of the driving roll, a vibrator and dog, a trip lever mounted for independent movement above the package holder, a trip finger mounted on the package holder and gradually moved towards the trip lever during the winding operation, means for adjusting the trip finger relative to the yarn package holder for varying the size of the completed yarn package, a dog controller pivotally mounted on the trip lever for pivotal movement thereon, and connections between the dog controller and dog for operatively positioning the dog and vibrator when the trip finger is raised a predetermined amount.

8. In a yarn winding machine having a yarn package driving roll and a yarn package holder, means for separating the yarn

package and driving roll when the yarn package has reached a predetermined size, comprising a lifter frame, yarn package lifter arms secured to said frame, a dog pivotally mounted on the lifter frame, a vibrator for engagement by the dog, a trip lever pivotally mounted above the yarn package holder, a trip finger mounted on the holder, a dog controller pivotally mounted on the trip lever, connections between the dog controller and dog, and a spring for normally holding the dog controller yieldingly relative to the trip lever.

9. In a yarn winding machine having a yarn package driving roll and a yarn package holder, means for separating the yarn package and driving roll when the yarn package has reached a predetermined size, comprising a lifter frame and yarn package lifter arms, a dog connected to the lifter frame for moving the latter to cause the lifter arms to lift the yarn package, a vibrator for engagement by the dog, a trip lever pivotally mounted above the yarn package holder, a trip finger mounted on the holder, a dog controller pivotally mounted on the trip lever, connections between the dog controller and dog, and variable spring tension means for normally holding the dog controller yieldingly relative to the trip lever.

In testimony whereof, I have signed my name to this specification.

EDWARD A. CUNNIEFF.
